(57) **CLAIM**

What is claimed is an ornamental design for a wireless remote control, as shown and described.

DESCRIPTION

FIG. 1 is a top, rear, right view of a wireless remote control showing our new design;

FIG. 2 is a rear elevational view thereof;

FIG. 3 is a front elevational view thereof;

FIG. 4 is a left elevational view thereof;

FIG. 5 is a right elevational view thereof;

FIG. 6 is a top plan view thereof;

FIG. 7 is a bottom plan view thereof; and,

FIG. 8 is a front, bottom, left view thereof.

The broken line in the figure drawings represents unclaimed environment only and forms no part of the claimed design.
